ROT-PROTECTING COVERING FOR WOODEN
POSTS, SLEEPERS, AND THE LIKE

Ernst Wortmann, Schwelm, Germany

Application February 18, 1936, Serial No. 64,603
In Germany November 6, 1933

1 Claim. (Cl. 20—100)

This invention relates to a rot-protecting covering for wooden posts, sleepers and the like, to be placed on the wooden post or the like and containing an impregnating means which is gradually dissolved by atmospheric moisture and penetrates into the wood to be protected.

In the protecting covering according to the invention the rot-preventing impregnating medium fills the meshes or holes of a wide-meshed net or 10 of a grid serving as carrier for the impregnating salt. In such nets or grids made of textile threads, for instance of jute threads or of cotton threads, the impregnating substance further fills the gaps between the fibres of the threads. The 15 mesh-width of the net or grid depends on the object to be fulfilled. Instead of a net or grid a porous or absorbent textile fabric may be employed. The impregnating salt is brought into the meshes or holes of the net or of the grid by 20 painting the net or grid with the impregnating substance or by saturating it with a liquid or pasty impregnating substance. The dissolved pasty impregnating material remains sticking in the net or grid like carrier and, if the carrier 25 consists of a textile fabric, for instance of coarse jute threads, it penetrates also in these threads. The quantity of the impregnating paste to be absorbed can be easily regulated by the mesh width and the thickness of the carrier. To im- 30 prove the adhesion of the impregnating medium on the carrier a binding agent may be added.

The adhering of the impregnating medium on a net or grid shaped carrier made of textile threads can be considerably increased by roughening the 35 same. The textile fibres pulled out partly from the individual textile threads by the roughening admix with the paste of impregnating salt when this paste is being applied and securely hold this paste on the carrier of the impregnating salt as 40 if it was held by numerous small hooks.

This protecting cover can therefore hold any desired quantity of impregnating substance which, as it is completely detached or dissolved by the atmospheric moisture, exerts its full effect.

45 The protecting covering can be easily produced.

The impregnating liquid formed from the impregnating substance by the contact with atmospheric moisture has the tendency to flow downwards, whereby for instance on wooden posts the 50 wood portions situated at higher points are less impregnated than the wood portions situated farther down. In order to compensate for this the upper part of the protecting cover has a thicker layer of impregnating substance than 55 the lower part so that from this upper part a

larger quantity of impregnating layer is formed than from the lower part. The protecting cover is usually in the shape of a long, narrow strip which is wound in spiral shape around the wooden post to be protected; in such rot-protecting covers that end of the strip which on a vertical post forms the upper part of the wrapping contains more impregnating salts.

To prevent dissolved impregnating salts from 10 penetrating into the ground, at points of the post and the like covered by the ground, the net or grid carrying the impregnating substance is fixed on an outer layer impermeable to water and consisting for instance of impregnated jute, asphalted cardboard and the like.

This form of construction has the especially 15 advantageous effect that not the entire layer of impregnating substance is dissolved at once by an exceptionally large quantity of moisture, for instance by heavy rain. The meshes and 20 holes of the net or grid filled with impregnating salt form a very great number of impregnating sections, framed and separated from each other by the threads of the net or grid, so that the 25 impregnating substance in these sections can be dissolved only gradually.

An embodiment of the invention is illustrated 30 merely by way of example in the accompanying drawing in Fig. 1 in longitudinal section and in Fig. 2 in elevation.

The carrier made of a textile fabric as net or 35 grid is designated by *a* and carries commonly used impregnating salts. *b* is a support which is flexible and impermeable to water. The impregnating substance in liquid or pasty state fills the meshes or holes of the carrier *a* and is also absorbed by the threads of the carrier. In rot-preventing covers in the shape of caps for post heads the support *b*, forming the outer side of the cap, has a few holes, or it is less strongly impermeable to water so that the atmospheric moisture can easily accede at the impregnating salt.

In Fig. 3 a net or grid-shaped carrier produced from textile threads is shown on enlarged scale, this carrier having been roughened prior to the 45 application of the impregnating substance. By the roughening numerous textile fibres *c* of short length have been pulled out. After the application of the impregnating substance the fibres are held in this substance and unite the same with 50 the carrier.

The impregnating substance for filling the meshes and holes of the net-like or grid-like carrier, may be of any suitable composition, a mixture of dinitrophenol 10%, sodium fluoride 90% 55

and zinc chloride being especially suitable, to which a little oil has been added to keep the substance plastic for a longer time.

I claim:

- 5 As an article of manufacture, a rot protecting cover for wooden posts, poles and the like, consisting of a unitary flexible band adapted to be wound on a post, said band comprising an integral and water impervious outer layer and an
10 inner layer comprising a wide meshed textile

fabric adapted to contact the surface of the post, said fabric layer being impregnated with water soluble wood impregnating salts, the meshes of said fabric forming relatively wide recesses, said recesses being filled with said salts, more of said salts being lodged in said fabric adjacent one side edge of said band than is lodged in said fabric adjacent the other side edge. 5

ERNST WORTMANN.
